United States Patent Office

Des. 228,690
Patented Oct. 16, 1973

228,690

INK MARKER

Francine Gomez, Paris, France, assignor to
Societe le Foyer, Paris, France

Filed Feb. 17, 1972, Ser. No. 227,324

Claims priority, application France Aug. 18, 1971

Term of patent 14 years

Int. Cl. D19—06

U.S. Cl. D74—17 B

FIG. 1 is a top plan view of an ink marker showing my new design;

FIG. 2 is a front view thereof;

FIG. 3 is a side view thereof;

FIG. 4 is a rear view thereof in the writing position with the cap placed on the opposite end of the ink marker; and

FIG. 5 is a bottom plan view of FIG. 2.

I claim:

The ornamental design for an ink marker, as shown.
